LIFESAVER VEST

Robert J. Boyle, Teaneck, N. J., assignor to Air
Cruisers Company, a corporation of New Jersey

Application March 11, 1950, Serial No. 149,135

6 Claims. (Cl. 9—17)

1

This invention relates to life vests and especially vests of the inflatable type adapted for emergency use.

In the case of both aircraft and surface vessels the emergency may occur at night, possibly with failure of the lighting system, and under such conditions it is desirable that the personnel as well as passengers be provided with a life-saving garment that can be quickly put on and inflated without likelihood of its being put on incorrectly.

In many cases the person, and especially a passenger, has had no previous instructions in the matter, and reliance upon printed instruction is not dependable because, even if there is light for reading them, they are likely to be not quickly grasped or to be confused by an excited person, especially when, as is usual practice, they are printed in three different languages.

The chief objects of my invention are to provide a life vest, with suitable fastening means, which can be put on either side foremost without substantially changing operations necessary for securing it upon the wearer; to provide a vest having fastening means the proper manipulation of which will be obvious to the wearer regardless of which side of the vest is foremost as he puts it on; to provide, in conjunction with these advantages, a vest and fastening means so constructed and arranged that they will maintain the body of the person in a proper attitude, with his head out of the water, even though he becomes unconscious; and to provide an assembly suitable for convenient use by women as well as men, in not requiring leg straps.

Of the accompanying drawings:

Fig. 1 is a front elevation, with parts broken away, of a vest embodying my invention in its preferred form, in flat, uninflated condition.

Fig. 2 is a perspective view of the same with the wearer in standing position and the vest inflated.

Fig. 3 is a side elevation of the same showing the attitude that the wearer assumes in the water.

Fig. 4 is a section of a seam portion of the vest.

Referring to the drawings, the assembly comprises a pair of yoke-shaped cells 10, 11 of air-impervious fabric, preferably made up in the flat from sheets of rubberized nylon fabric which are given closed-cell form by seaming around their margins, as at 10^a and 11^a.

These cells permissibly are of the same size and shape; are placed one upon the other in registry; and are permanently joined to each other only at their inner margins at the back of the wearer's neck, as at 12, and at the inner margins of the lower parts of their leg portions, as at 13.

For inflation of the cell 11 it carries upon its outer face nearest the cell 10 a mouth-inflation tube 10^b and a well-known carbon-dioxide inflation device 10^c. Likewise the cell 10, for its inflation, carries upon its outer face nearest the

cell 11 a mouth-inflation tube 10^b and a carbon-dioxide inflation device 10^c.

Upon inflation each cell of course bulges out in its yoke-shaped medial zone, all of the margins of each cell thus being spread away from the corresponding margins of the other cell, except where the margins of the two cells are permanently secured together, at 12 and 13.

To permit such spreading apart of the margins upon inflation, and at the same time hold the two cells in orderly arrangement when they are in flat, uninflated condition, the margins that are to spread apart are provided with automatically releasing fastener means, such as the snap-fasteners 14, 14, adapted to separate under the force of the inflation pressure.

The shape of the cells in the flat is such that they fit closely around the front of the neck, under the jaws, of the wearer, and upon inflation the bulging of the two cells at that position causes them to fit firmly in the bays between the head, including the jaws, and the shoulders and neck of the wearer, and thus keep his face lifted, even though he becomes unconscious. At the same time the lifting of the upper cell, 10, and especially its leg portions, gives a proper center of buoyancy, in relation to the center of gravity, for maintaining the wearer in the position, in the water, of leaning backward about 15° to 20° from vertical position, so as to give the face of the wearer the highest possible elevation and to provide the wearer with the maximum visibility and mobility, as for locating and boarding a life raft.

The cell assembly as described is, in the flat, symmetrical with respect to a middle vertical plane between the two cells, and with respect to a middle vertical line in that plane, so that the behavior of the cells upon inflation is the same regardless of which side of the vest is foremost as the wearer puts it on.

The fastening means, having like advantage, comprises a back piece 15 having its upper end portion freely extending inward between the two cells and anchored to the inner margins only of the two cells where they are permanently secured to each other, at 12, at the back of the neck of the wearer, so that its action is the same whichever one of the cells it has under it in use, the other cell being free to rise without restriction and suitably snug itself about the neck of the wearer.

Secured to and extending horizontally in each direction from the lower margin of the back piece 15 is a waist strap of which the respective reaches are designated 16 and 17 in the drawings. Preferably the back piece 15 is of such width that the reaches of the waist strap have their junction with it at positions that can be easily reached by the wearer.

Adjustably mounted upon each of these reaches is a spring-tongue buckle 18 having a tail loop 19 to which is secured by a suitable reach of webbing 20 a D-ring 21. These D-rings are adapted

to be engaged with respective harness snaps 22 which are mounted upon and extend horizontally from the lower end of the seam webbing 13, which extends downward, at 13^a, a considerable distance beyond the lower ends of the cells.

To facilitate the tightening of the two reaches 16, 17 of the waist strap after snaps 22, 22 have been engaged in the rings 21, 21, each of the reaches has on its end a hand-grip enlargement 23, Figs. 1 and 2.

The tongue of each of the buckles 18, formed with teeth and backed by a spring, holds the reaches of the waist strap in whatever condition of tautness is given them by simply pulling their hand-grip ends away from their anchorage snaps 22.

As the anchorage snaps 22 are always at the middle plane, fore-and-aft, of the assembly, where the two cell margins are permanently joined, their action and that of the waist-strap reaches are the same regardless of which side of the vest is foremost as the wearer puts it on, and the leg portions of the cells are free to rise, to the limit determined by the extension reach of the seam webbing 13, for full inflation of the cells and for proper positioning of the center of buoyancy. The legs of the cells being permanently joined at their inner margins of their lower or forward parts, the danger is avoided of their not being properly drawn together by tie members as in earlier vests. Such earlier vests are usually tied in the front and it is left to the inexperienced wearer to allow either long or short reaches. Other types of vests have no positive means whatsoever for drawing the inflation elements together in the front and in both of these conditions the legs of the inflation elements may take a position at the sides of the body which permits the user to fall face forward in a position from which it is very difficult for him to right himself, if, in fact, he does not drown. Attaching the four legs of the inflation elements together in close relationship and with a spacing means such as the extension 13^a of the seam webbing 13, thus permitting the lower or forward ends to drift out away from the body when inflated, assures a position of the center of buoyancy out in front of the wearer so that it is impossible for him to get in a wrong attitude in the water.

The material of the cells preferably is nylon fabric, 24, Fig. 4, faced with rubber 25 and joined in a cemented seam as shown clearly in Fig. 4, the seam being reinforced by a folded strip of tape 26 having a rubber facing 27.

Each face of the back piece 15 is well adapted to have indicia such as printed instructions, 15^a placed upon it.

The mode of operation is believed to have been adequately described in conjunction with the description of structure.

As the wearer can not anchor the belt-strap rings 21 to each other, he may be reasonably expected to locate the snaps and connect the rings to them respectively. Two snaps, each off-center, are provided rather than a single snap, to avoid the likelihood of strain being imposed upon the spring tongue of the snap, which might occur if both rings were engaged with a single snap.

The type of harness makes one size vest fit all sizes of persons from a child to the largest person. The flotation, the comfort, the floating attitude, the self righting movement are equally correct no matter what size person is wearing 75

it. In the case of children each reach of the waist strap can be given a turn about the upper part of the child's thigh before engaging the ring 21 with the snap 22.

Modifications are possible within the scope of the invention as defined in the appended claims.

I claim:

1. A life-saver vest comprising a pair of superposed, yoke-shaped, inflatable, flexible cells adapted to surround and project forward and downward from the neck of the wearer, the two cells being permanently joined to each other at their inner margins at the back-of-the-neck position and at their inner margins in the lower parts of their leg portions, the two pairs of leg portions also being joined together at that position, a back piece having its upper end portion extending inward between the cells and joined to their joined inner margins at the back-of-the-neck position, said piece being adapted to extend down the back of the wearer, belt straps extending in opposite directions from the lower end of the back piece, and means for detachably connecting the forward portions of the belt straps to the permanently joined inner margins of the lower portions of the four leg portions of the cells.

2. A vest as defined in claim 1 in which the last said means comprises a tie member secured to and projecting downward from the joined inner margins of the leg portions of the cells.

3. A vest as defined in claim 1 in which the last said means comprises gripping members slidably mounted on the belt straps, for tightening of the belt straps after connection of the gripping members to the joined margins of the cells.

4. A vest defined in claim 1 in which the last said means comprises a pair of snaps, secured to the joined leg portions of the cells and respectively off-center in opposite directions with respect to the middle line of the joined margins of the cells, and comprises rings mounted on the belt straps for detachable engagement by said snaps respectively.

5. A life-saver vest comprising a pair of superposed, yoke-shaped, inflatable, flexible, upper and lower cells adapted to surround and project forward and downward from the neck of the wearer and having respective fluid-distensible parts, one upon the other, at the back-of-the-neck position, said cells at that position having at least portions of their inner margins joined to each other, and a harness member extending inward between the said fluid-distensible parts of the upper and lower cells and joined to the said joined portions of their inner margins at the said position.

6. A vest as defined in claim 1 in which the back piece is of such substantial width that its junctions with the belt straps are at substantial distances from the vertical middle line of the wearer's back.
